(57) **CLAIM**

The ornamental design for a jet regulator, as shown and described.

DESCRIPTION

The patent or application file contains at least one drawing executed in color. Copies of this patent or patent application publication with color drawings will be provided by the Office upon request and payment of the necessary fee.

FIG. 1 is a top perspective view of a jet regulator in accordance with a first preferred embodiment of my new design; FIG. 2 is a front elevational view thereof, rear and side elevational views thereof being the same;

FIG. 3 is a top perspective view of a jet regulator in accordance with a second preferred embodiment of my new design; and,

FIG. 4 is a front elevational view thereof, rear and side elevational views thereof being the same.

The broken lines in the figures are for illustrative purposes only and form no part of the claimed design.

The bottom view of the jet regulator of the first and second preferred embodiments is not shown in the drawings or described in the specification and, therefore, forms no part of the claimed design.
